UNITED STATES PATENT OFFICE.

JOHN D. LINSS, OF OKLAHOMA, OKLAHOMA.

SMOKEHOUSE.

1,354,317.

Specification of Letters Patent. Patented Sept. 28, 1920.

Application filed December 24, 1919. Serial No. 347,070.

To all whom it may concern:

Be it known that I, JOHN D. LINSS, a citizen of the United States, residing at Oklahoma, in the county of Oklahoma and State 5 of Oklahoma, have invented certain new and useful Improvements in Smokehouses, of which the following is a specification, reference being had to the accompanying drawings.

10 This invention relates to smoke houses, and particularly to smoke houses such as are used in large butchering and packing establishments for smoking meat, fish, sausage, hams, bacon, etc.

15 The general object of this invention is to provide a smoke house of such construction that the meats being smoked may be either subjected to the direct heat of the fire or not as deemed most desirable.

20 A further object is to provide means whereby the heat may be carried off to the atmosphere and the meats thus not subjected to the direct heat of the fire, while the smoke may be carried through the smoke 25 house and the meats subjected thereto.

A further object is to provide a smoke house so constructed that the shrinkage of meat in the process of smoking will be greatly reduced or entirely eliminated.

30 And another object is to provide a smoke house wherein the meat will be absolutely safe and prevented from being directly acted on by the fire.

Another object is to provide a smoke 35 house of this character wherein a separator is used which will permit the smoke to pass into the smoke house but the heat to pass directly up into a stack.

Another object is to provide a smoke 40 house of this kind with a fire box, dampers normally closed to prevent the direct passage of heat from the fire box into the smoke house but which may be opened to permit said direct passage of heat, and provide means whereby the smoke may be 45 caused to pass into a separator so constructed that the smoke may be then directed by a suitable damper into the smoke house and the heat caused to pass up into the 50 air through a stack, or both the smoke and heat may be caused to pass into the stack.

Another object is to provide dampers separating the fire box from the stack which

are air cooled and non-conductors of heat. 55

Other objects will appear in the course of the following description.

My invention is illustrated in the accompanying drawings, wherein:—

Figure 1 is a front view of a smoke house 60 constructed in accordance with my invention;

Fig. 2 is a vertical transverse sectional view of the smoke house and separator;

Fig. 3 is a vertical section on the line 65 3—3 of Fig. 2;

Fig. 4 is a fragmentary section on the line 4—4 of Fig. 2.

Referring to these drawings, 10 designates the smoke house proper which is 70 closed on three sides and on the fourth side is provided with doors 11 and 12 which, when open, permit the removal of the racks from the interior of the smoke house, but which may be closed, and locked by means 75 of the latch bar 13 engaging in the keeper 14. The interior of the smoke house is to be provided with cleats 15 whereby the racks may be supported therein. Below the smoke house proper or compartment 10 is 80 a fire box, designated generally 16, provided with a fire door 17 of any suitable construction but shown as sliding in guides 18. Forming the upper part of the fire box and the bottom of the smoke house proper 85 are a plurality of dampers 19, each damper being pivotally mounted upon a longitudinal shaft 20, the shafts of these dampers extending out through the front of the fire box above the door 17 and being provided 90 with suitable means whereby they may be rotated and held in adjusted position.

These dampers are, of course, to be made of refractory or non-conductive material, and preferably the dampers are somewhat 95 oval in cross section and hollow, as at 21. The shaft 20 of these dampers pass out through the exterior wall of the fire box and are there provided with means whereby they may be rotated, and access to the dampers 100 may be had by means of a slot, normally closed by a hinged door 22. Fresh air may pass into the smoke house by opening the door 22, and by opening this door 22 air may be allowed to pass into the hollow dampers, 105 thus cooling them off.

Disposed at one side of the fire box and smoke house proper is a separator casing 23

which may be made of metal or other suitable material and is provided with a detachable top 24. A duct 25 leads from the upper portion of this separator into the smoke house above the dampers 19 therein, and a pipe 26 leads from the fire box into the separator and there engages a branch pipe 27 which is downwardly inclined toward one end and at its lower end is connected 10 to an upwardly extending pipe 28. The upper end of the pipe 27 is flared at 29, and this enlarged end is disposed in the upper portion of the separator. Disposed within the pipe 27 is a small pipe 29^a whose lower 15 end is approximately even with the pipe 26, this small pipe 29^a extending out through the enlarged, upper end of the pipe 27. The outer end of this pipe 29 is supported by a spider having perforations 29^b. The pipe 28 20 is provided at one point with an opening 30, and adapted to cover or uncover this opening is a damper 31 mounted upon an arm 32 which, in turn, is mounted upon a shaft or spindle 33 extending through the end of 25 the separator and provided with a handle 33^a. A damper 34 is disposed in this spindle. It will be obvious now that when this handle is turned in one direction, the damper 31 will close the opening 30, and under 30 these circumstances the damper 34 will be opened. When, however, the damper 31 is shifted fully away from the opening 30, the damper 34 will be closed. Mounted upon this pipe 28 and extending upward therefrom 35 is a stack 35, and extending from an opening 36 in the top of the smoke house 10 is a flue 37 which connects with this stack 35.

The duct 25 is controlled by means of a damper 38 which is illustrated as a sliding damper mounted upon a rod 39 which extends out to the front of the smoke house above the fire box, and the duct or pipe 26 is controlled by a damper 40, in turn connected to a rod 41 which extends out through 45 the front wall of the fire box, whereby the damper may be operated. Preferably, the pipe 26 is provided with a downwardly or laterally extending branch 42 which is open and extends from the bottom of the pipe 26. This branch 42 and the openings 29^b 50 permit the smoke to escape freely into the separator, while the lighter heated products of combustion will be drawn upward through the pipe 28 to the stack 25.

55 Preferably, a hollow partition wall 43 of refractory material, and which may be of non-conductive material, is disposed across the separator, as indicated in Fig. 2. This hollow partition wall does not extend entirely across the separator, but only above the pipe 26. This wall is provided with relatively large lower openings and relatively small upper openings, whereby the heat and smoke may circulate through the 60 separator. It is to be understood that the 65

opening 42 may be located either to open downward or open toward the forward end of the separator, as desired.

In the operation of this device, if it is desired that the meat, fish or other articles 70 within the smoke house be submitted to the direct action of heat, then the dampers 19 are opened to a greater or less extent so as to permit the heat and smoke to pass upward and act upon the materials hanging 75 within the smoke house. The heat and smoke will pass out through the branch pipe 37 and up the stack. If, on the other hand, it be desired that the material within the smoke house be not subjected to the 80 direct heat, but subjected entirely to the smoke, then the dampers 19 are closed, thus cutting off the action of direct heat and the smoke and heated products of combustion will pass into the separator through the 85 pipe 26, the heat passing up the stack, as before stated, to some extent and a portion of the heat and the smoke passing into the separator itself and through the duct 25 into the smoke house. Of course, the amount of 90 heat and smoke which passes into the smoke house may be controlled by the damper 38 or by the damper 40. If the damper 31 be opened, then the damper 34 will be closed, as before explained, thus allowing the smoke and heat to pass out through pipe 27 into the separator and thus into the stack 35 through opening 30. On the other hand, if the damper 31 be closed, then the damper 34 is opened and direct connection established which will tend to carry the smoke and heat off through the stack 35. The 95 particular shape of the pipe 27 with its interior pipe 29^a will tend to cause separation of the smoke and heat so that if the damper 100 31 be closed and the damper 34 be opened, the heat will tend to pass up through the stack 35, but the smoke will pass upward out of the enlarged open end of the pipe 27 and pass into the separator and from 105 the separator into the smoke house and thence out by the flue 37. In other words, a draft will be created from the upper portion of the separator and out through the pipe 37 which will tend to carry the smoke 110 this way, while most of the heat will pass upward through the stack 35. If, however, the damper 31 be opened, then the heat and smoke both will tend to pass directly into the 115 stack 35 and so out. When bacon, sausage, or other meat is being smoked which does not require much heat, the dampers 19 are closed and the dampers 38 and 40 are opened. Then the smoke alone goes into 120 the smoke house. If it be desired to open the smoke house door, then the damper 38 is closed and the damper 31 is closed and heat and smoke are carried out through 125 stack 35. Thus, the smoke will not pass through the smoke house into the building 130.

where the smoke house is located. When the outer doors 11 and 12 are closed, then the damper 38 is opened and the damper 31 is opened, and then the smoke will pass 5 from the separator into the smoke house again.

In case meats are being smoked which require plenty of heat, the dampers 19 are opened and dampers 38 and 40 are closed.

10 That throws the direct heat into the smoke house and at the same time this heat and smoke can be regulated by the dampers 19. It is also possible to withdraw part of the heat and smoke by opening the damper 40

15 as well as the dampers 19 so that some portion of the smoke and heat will pass out through the pipe 26 and so out to the stack. When the meat has been properly treated, the dampers 40 and 41 are opened. Then the 20 heat and smoke will both go out of stack 35 and by closing the dampers 19 entirely, no smoke will pass into the building even when the doors 11 and 12 are open. The damper 31 and damper 34 are both on the

25 same operating member. It will be understood that in large smoke houses where there are many compartments, or in which the smoke house is longer than it is wide, there will be a plurality of the dampers 38 and 40, 30 a plurality of pipes 26 with their connections to the stack 35, and all of the dampers will be operated by a single unitary means.

It will thus be seen that the meat within 35 the smoke house may be subjected to any desired degree of heat, either direct or indirect, and to any desired degree of smoke, and that all of the smoke may pass through the smoke house or only a portion of the smoke may pass through the smoke house, 40 and that this smoke will be heated to a degree which will make it most effective in its action on the meats hung within the smoke house.

One of the great troubles with the smoking of meat of all kinds is the shrinkage 45 in the meat itself, which is due to the direct application of the heat to the meat, and there is a great loss in meat smoking establishments because of this shrinkage. Furthermore, there is always danger in all 50 smoke houses known to me of the meat becoming too greatly heated consequent upon the fire burning too strongly, but this is entirely overcome in my construction by 55 the arrangement of dampers which prevents the direct action of the fire on the meat, and which permits the meat to be subjected to a long continued smoking at a relatively low heat, or to a relatively rapid smoking 60 at a relatively high degree of heat. Preferably, the smoke house, the separator, and fire box will be formed of cast iron, though this is not necessarily the case, as other materials might be used in whole or in part. 65 Of course, it is obvious that this smoking

apparatus may be constructed on any desired scale and that the number of dampers separating the fire box from the smoke house proper and the number of dampers for controlling the passage of heat and smoke into 70 the separator and from the separator into the smoke house may be varied, depending upon the size of the apparatus and its capacity.

I do not wish to be limited, therefore, to 75 the exact construction shown or to the exact arrangement of parts, as these may be varied in many ways without departing from the spirit of the invention.

I claim:—

1. A smoke house proper having means 80 for supporting meat therein, a fire box disposed beneath the smoke house, non-conductive dampers separating the fire box from the smoke house and shiftable to an open or closed position, and manually controllable means for directing the smoke from the fire box and into the smoke house when the dampers are closed.

2. A smoke house, a fire box thereunder, 90 dampers disposed between the fire box and the smoke house and shiftable to entirely separate the smoke house from the fire box or permit the direct passage of heat from the fire box into the smoke house, a smoke 95 and heat separator, a pipe extending from the fire box into the separator, a duct extending from the separator into the smoke house, dampers controlling said pipe and duct respectively, and damper controlled 100 means for carrying off heat from the separator and smoke from the upper end of the smoke house.

3. A smoke house, a fire box thereunder, 105 dampers disposed between the fire box and the smoke house and shiftable to entirely separate the smoke house from the fire box or permit the direct passage of heat from the fire box into the smoke house, a smoke and heat separator having a duct leading 110 into the smoke house at the lower end thereof above the fire box dampers and controlled by a damper, a pipe leading from the fire box into the separator and controlled by a damper, said pipe at its outer end having 115 two branches, one opening into the separator and the other communicating with an upwardly extending flue, a stack into which said flue opens, a branch pipe leading from the top of the smoke house into said stack, 120 and means for opening communication directly between the interior of the separator and said flue.

4. A smoke house, a fire box thereunder, 125 dampers disposed between the fire box and the smoke house and shiftable to entirely separate the smoke house from the fire box or permit the direct passage of heat from the fire box into the smoke house, a smoke and heat separator, the separator having a 130

- 4
- duct leading into the smoke house at the lower end thereof above the fire box dampers and controlled by a damper, a pipe leading from the fire box into the separator and controlled by a damper, said pipe at its outer end having two branches, one opening into the separator and the other communicating with an upwardly extending flue, a stack into which said flue opens, a branch pipe leading from the top of the smoke house into said stack, and means for opening communication directly between the interior of the separator and said flue, said means comprising an opening in the flue, and a 10 manually shiftable damper normally closing said opening but adapted to be shifted away from the opening to permit the passage of smoke through said opening into the flue.
20. 5. A smoke house having means therein for supporting materials to be smoked, a fire box beneath said smoke house, hollow, air cooled, refractory, non-heat conductive dampers disposed between the fire box and the 25 smoke house and shiftable into a position to directly connect the fire box with the smoke house cut off for communication between the two, a separator casing connected to the smoke house, a duct leading from the upper portion of the separator casing into the lower portion of the smoke house above the fire box dampers, a manually controlled damper controlling passage through said duct, a pipe leading from the 30 fire box into the separator, a manually controlled damper controlling passage through said pipe, a branch pipe at the end of the first named pipe, a branch pipe extending at an inclination to the horizontal and being 35 open at its upper end for the discharge of smoke, the lower end of said branch pipe being connected to an upwardly extending flue, a stack extending upward from said flue, a branch flue extending from the top of the smoke house and discharging into the 40 stack, said first named flue being provided with an opening, and a manually actuatable damper normally closing said opening but shiftable to uncover the opening to permit 45 smoke to pass into the flue.
6. A smoke house, a fire box therein, dampers disposed between the fire box and the smoke house and shiftable to entirely separate the smoke house from the fire box or 55 permit a direct passage of heat from the fire box into the smoke house, a smoke and heat separator, the separator having a duct leading into the smoke house at the lower end thereof above the fire box dampers, and controlled by a damper, a pipe leading from the fire box into the separator and controlled by a damper, said pipe at its outer end having two branches, one 60 opening into the upper end portion of the separator and the other extending down-

ward and communicating with an upwardly extending flue, a stack into which said flue opens, a branch pipe leading from the top of the smoke house into said stack, and means for cutting off communication between said last named branch and the upwardly extending flue or establishing communication between the last named branch and the upwardly extending flue and for opening communication between the upper portion of the separator and said flue.

7. A smoke house, a fire box therein, dampers disposed between the fire box and the smoke house and shiftable to entirely separate the smoke house from the fire box or permit a direct passage of heat from the fire box into the smoke house, a smoke and heat separator, the separator having a duct leading into the smoke house at the lower end thereof above the fire box dampers and controlled by a damper, a pipe leading from the fire box into the separator and controlled by a damper, said pipe at its outer end having two branches, one opening into the upper end portion of the separator and the other extending downward and communicating with an upwardly extending flue, a stack into which said flue opens, a branch pipe leading from the top of the smoke house into said stack, and means for establishing or cutting off communication between said last named branch and the upwardly extending flue and for opening communication between the upper portion of the separator and said flue, said means comprising an opening in the flue, a damper disposed below said opening and having a spindle, and an arm extending from the spindle and carrying a damper adapted to be disposed over the opening in the flue to close it and said spindle having a handle whereby it may be rotated.

8. A smoke house having means therein for supporting materials to be smoked, a fire box beneath the smoke house, dampers disposed between the fire box and smoke house and shiftable to entirely separate the two, or permit the direct passage of heat and smoke from the fire box into the smoke house, a smoke and heat separator casing having a duct leading into the smoke house at the lower end thereof above the fire box dampers, and controlled by a damper, a pipe leading from the fire box into the separator and controlled by a damper, said pipe at its outer end having two branches, one extending upward and the other downward in an opposite direction, the upwardly extending branch being flared at its top, the downwardly extending branch being contracted toward its lower end and being connected to an upwardly extending flue, a relatively small pipe disposed within the upwardly extending branch and opening at its outer end coincident with the opening of

the upwardly extending branch, this pipe being contracted at its lower end, a stack into which the flue opens, a branch pipe leading from the top of the smoke house into 5 said stack, and means for opening communication directly between the interior of the separator and said flue and closing

connection between the downwardly extending branch and the flue or opening said last named connection and closing the first 10 named connection.

In testimony whereof I hereunto affix my signature.

JOHN D. LINSS.
